[57] CLAIM

The ornamental design for a tie-down clamp for a pickup truck, as shown and described.

DESCRIPTION

FIG. 1 is a perspective view of a tie-down clamp for a pickup truck showing my new design;

FIG. 2 is a perspective view thereof showing the article in use;

FIG. 3 is a top plan view thereof;

FIG. 4 is a front elevational view thereof;

FIG. 5 is a left side elevational view thereof;

FIG. 6 is a rear elevational view thereof;

FIG. 7 is a right side elevational view thereof; and,

FIG. 8 is a bottom plan view thereof.

The broken line showing of a truck side wall is for illustrative purposes only and forms no part of the claimed design.
